UNITED STATES PATENT OFFICE.

EUGENE L. MESSLER, OF PITTSBURGH, PENNSYLVANIA.

REFRACTORY PLUG FOR INGOT MOLDS.

Application filed April 24, 1928. Serial No. 272,425.

This invention relates to an improvement in ingot mold plugs and the like.

As is well known in the art, ingot molds are usually constructed to mold an ingot of metal with its large end up. This practice permits the ingot to be readily withdrawn from the mold with the aid of the ordinary stripping ram which passes through the bottom hole of the, so called, "big-end up" ingot molds.

Over a period of years next preceding the filing of this application a great many devices have been evolved to plug the aforesaid bottom hole of the ingot during the pouring and cooling of the metal therein. These devices have proven in many instances to be too difficult to properly install in the ingot mold or have been of such form or shape that their transportation and storage was a difficult problem to contend with.

The object of this invention is, therefore, to provide an ingot mold plug which is composed of a suitable cementitious heat resisting composition, and which is so formed that its installation and transportation or storage may be made with relative facility.

In the accompanying drawings Figure 1 is a plan view of a large size plug of this invention; Figure 2 is a vertical central sectional view of the same; Figure 3 is a plan view of a smaller type of plug embodying the same general structure as the previous plug; Figure 4 is a central vertical sectional view of the plug shown in Fig. 3; and Figure 5 is a central vertical sectional view through an ingot mold showing a plug of this invention installed therein.

Although the formation of the ingot mold plug is the essence of this invention, it is well to note that the composition described and claimed in my co-pending application, Serial No. 220,288, filed September 17, 1927, has proven to be the best known substance of which to make the plug.

Heretofore it has been the practice to make plugs of this general structure of relatively great depth; that is, the plug would extend downwardly approximately half the depth of the bottom hole 1 of the ingot mold 2. It was further the practice to have the sides of the plug and the sides of the hole substantially parallel. In the event that any irregularities were on the walls 1^a of the bottom hole 1, it is obvious that a plug of this nature would not seat tightly, and as a result some molten

metal would escape during the pouring operation.

To overcome this disadvantage and to permit a ready centering of the plug 5, as shown in Fig. 5, the side surface 5^a of the plug 60 is tapered about five degrees more than the side wall 1^a of the hole 1. This difference in taper permits a line contact between the plug 5 and the ingot mold 2 at 4. Obviously the plug 5, due to its taper, is free to pass over 65 slight irregularities of the surface 1^a, and for the same reason the plug is easily dropped into place to seat itself.

Since the line contact between the ingot mold and the plug is adjacent the upper edge 70 of the plug; as shown at 4 in Figure 5, it should be understood that any irregularities in the mold opening 1 tending to destroy the line contact do not in fact do so. This is for the reason that the weight of the plug 75 and the reaction of the molten metal first striking the plug causes the upper edge thereof to chip and spall around the irregularities, and in this manner the plug will settle. 80

With this particular shape of plug it was found that its depth need not be more than twenty per cent of its diameter for the twelve inch sizes, and in the six inch sizes it has been 85 found that forty per cent of the diameter gives sufficient depth of material to result in the necessary strength.

Figures 1 to 4 inclusive give a detailed idea of the relative proportions of the twelve inch plug 3 and the six inch plug 5. It is to be 90 understood that sizes intermediate of the plugs shown may be constructed having the dimensions determined by the proper ratio to these plugs.

The relatively flat or disk shape of the 95 plugs permits them to be packed very close together for either transportation or storage. This feature alone would prove them very valuable to the trade, since a large portion of the cost of the ingot mold plugs is reflected from transportation charges which are greatly reduced due to lesser weight per plug. That is, the plugs of the present invention, due to their composition and decreased thickness, weigh about sixty per cent 100 as much as the plugs now in use.

What I claim is:

1. An ingot mold plug having a side surface tapered five degrees or more than the taper of ingot mold hole wherein it seats to 110

permit only a line contact between said plug and the ingot mold.

2. An ingot mold bottom plug having its sides formed with a single surface tapered to a greater degree than the wall of the bottom hole of the ingot mold.
- 5 3. An ingot mold plug of disk shape hav-

ing its sides formed with a single surface tapered to a greater degree than the wall of the bottom hole of the ingot mold.

10 In witness whereof, I hereunto set my hand.

EUGENE L. MESSLER.
